CLAIM

The ornamental design for a basketball stand toy, as shown and described.

DESCRIPTION

FIG. 1 is a perspective view of a basketball stand toy, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings depict portions of the basketball stand toy, that form no part of the claimed design. The dash dot dash broken lines of the basketball stand toy in FIG. 3 illustrates a boundary line and forms no part of the claimed design.

1 Claim, 7 Drawing Sheets
